PIPE

Lynn M. Francis, Birmingham, Mich.

Application June 25, 1934, Serial No. 732,203

1 Claim. (Cl. 131—12)

This invention relates to smoking pipes, and has for its principal object to provide a new and improved construction of a pipe in which there is incorporated in a relatively small pipe a long passage for the smoke, whereby a cool smoke is obtained.

Another object of the invention is to provide the bowl portion of the pipe with a plurality of communicating passageways to provide a circuitous 10 passage, thereby to considerably lengthen the distance which the smoke must traverse from the bowl to the mouth-piece of the pipe, and which passageways are so arranged that they may be readily bored to furnish communication with the 15 bottom of the bowl by means of an ordinary drill, both passages being readily accessible through the opening which serves for connection to the bowl of the mouth-piece. This construction also enables the smoke passages to be readily cleaned by 20 the use of an ordinary pipe cleaner.

A further object is to incorporate with the stem, or mouth-piece of the pipe, a tube, preferably of metal, which projects into one of the passages formed in the stem portion of the bowl to define 25 with such passage an additional circuitous path for the smoke to traverse.

Although I am aware that it is not broadly new to provide smoking pipes with various means to define a circuitous passage for the smoke, such 30 pipes as heretofore constructed have, as far as I am aware, been of rather complicated construction which are either very difficult to manufacture, or were of cumbersome construction with a resulting unattractive appearance. It is, therefore, a further object of the present invention to 35 provide a smoking pipe with a circuitous smoke passage of simple construction that can be readily manufactured but yet, withal, is of neat, compact and attractive appearance.

The above and other objects will appear more fully from the following, more detailed description, and by reference to the accompanying drawing forming a part hereof, wherein:

Fig. 1 is a perspective view of one form of pipe constructed in accordance with the principles of the present invention, and

Fig. 2 is a central longitudinal section through the pipe shown in Fig. 1.

As shown in the drawing, the pipe comprises a 50 bowl member 10, having the usual bowl 11, which serves as a receptacle for the tobacco. The member 10 is also provided with a stem portion 12, which as shown, is sufficiently thickened to provide sufficient material to enable a main passage- 55 way 13 and an auxiliary passageway 14 to be

drilled into the stem. The passageway 13 is closed, as shown, at its inner end, and its outer end communicates with a counterbore 15 in which is adapted to be engaged the reduced end 16 of the mouth-piece 17.

The mouth-piece 17 is provided with the usual bore, or passage 18, and has suitably secured to its inner end a small tube 19 which preferably is of metal and which tube projects into the main passage 13 and terminates short of the inner closed 5 end thereof.

The auxiliary passage 14 communicates at one end with the bowl 11 adjacent the bottom thereof, and at its other end with the bottom of the main passage 13 adjacent to the counterbore 15.

As will be seen from an inspection of the drawing, and the foregoing description, the construction results in the provision of a long, circuitous passage for the smoke from the bowl to the mouth-piece, the smoke being drawn through the 20 auxiliary passage 14 to the rear end of the main passage 13, from which it flows forwardly through said main passage to be drawn through the metal tube 19 and passageway 18 to the smoker's mouth.

It will be noted the construction is such that 25 the auxiliary passage 14 is a straight passage and arranged at such an angle as to be readily accessible from the counterbore 15 of the stem portion 12 of the member 10. Consequently the auxiliary passageway 14 can be readily drilled with a small, 30 straight drill directly from the open end of the counterbore 15. Likewise, the main passageway 13 is a straight passage that can also be drilled straight in from the counterbore 15. As both 35 passages 13 and 14 may be said to open directly into the counterbore 15, these passageways may be readily cleaned by removing the mouth-piece 18 and by the use of any ordinary pipe cleaner.

The tube 19 preferably being made of metal, 40 serves to insure the condensation of any moisture on this tube and prevents such moisture from finding its way to the auxiliary passage 14 and thence to the bowl of the pipe.

It will be seen that a pipe constructed as above described will have a smoke passage nearly twice 45 the distance of a pipe of conventional design of about the same dimensions, and that the cooling effect of a very long stemmed pipe is obtained in a pipe of small, compact size that may be readily carried in the user's pockets.

It will also be noted that the construction is 50 such that any saliva which might flow into the passage 18 will be obstructed by the closed end of the main passage 13, and as the pipe in use would ordinarily be held in the smoker's mouth at a 55

slight downward angle, such saliva, or moisture, cannot find its way to the auxiliary passage 14 and thence to the bowl. Actual use of pipes constructed in accordance with the principles herein disclosed show that any moisture has a marked tendency to condense upon, and adhere to, the small metal tube 19. Such use also shows that no moisture ever collects in the tobacco at the bottom of the bowl, such as occurs with pipes of conventional design.

While I have shown the invention embodied in a pipe having a straight stem, it will be readily understood that the invention is not limited to a pipe of the particular configuration shown in the drawing, but that the invention is readily applicable to pipes having curved stems, or bowls of any desired shape or size.

It will also be seen that the present type of construction is readily applicable to bowls constructed of any desirable material, such as briar, meerschaum, corn cob, or any of the usual materials used for the construction of pipes. Likewise the simplicity of the mouth-piece construction enables any of the well known and desirable materials, such as amber, to be used for the construction of the mouth-piece.

Although I have shown and described the main passage 13 as provided with a counterbore 15, it will be understood that the use of such counter-

bore is not essential but that the main passage may be made of sufficiently large diameter to receive the mouth-piece directly.

I claim:

In a smoker's pipe, a bowl portion having a 5 tobacco receiving chamber therein and a thick stem portion extending substantially at right angles to said chamber, the upper and lower walls of said stem portion merging with said bowl portion and converging towards the end of said 10 stem portion to form a bit receiving end of substantially circular cross sectional configuration, said bit receiving end being counterbored and said stem portion having an enlarged main bore extending substantially perpendicular to said 15 chamber, in axial alignment with said counterbore substantially in parallelism with the upper 20 wall of said stem portion and having a closed inner end, and an auxiliary bore of small diameter extending at an acute angle to and below said main bore substantially in parallelism with the lower wall of said stem portion with its inner 25 end communicating with the lower end of said chamber and its outer end communicating with said main bore adjacent to said counterbore and so that the prolongation of its axis intersects the center of said counterbore at the outer end thereof.
